RECOVERY OF SULFONIC ACIDS FROM PETROLEUM FRACTIONS

John F. Hutto and William Nelson Axe, Bartlesville, Okla., assignors to Phillips Petroleum Company, a corporation of Delaware

Application January 2, 1952, Serial No. 264,436

10 Claims. (Cl. 260—504)

This invention relates to sulfonic acids. In one of its more specific aspects, this invention relates to the recovery of water insoluble sulfonic acids. In another of its more specific aspects, it relates to the recovery of sulfonic acids as a by-product of a process for oxidation of petroleum stocks with SO_3 or sulfuric acid. In another of its more specific aspects, this invention relates to the separation of sulfonic acids and an oil phase containing products of oxidation produced in a process for oxidizing petroleum with SO_3 .

Ashless detergents for use in lubricating oils and greases are prepared by the oxidation of petroleum with SO_3 as disclosed by W. B. Whitney in copending U. S. application, Serial No. 304,659, filed August 15, 1952. Such oxidized products must be substantially neutralized before their incorporation in lubricating oils and greases so as to obtain the best possible results therefrom.

It is known that some sulfonic acids are water-soluble while others are substantially water-insoluble. The water-soluble sulfonic acids can be substantially removed from the oil phase containing the oxidized material by water-washing. Additional sulfonic acids can be removed by alcohol washing of the oil phase containing the oxidized materials. The oil phase product obtained from this alcohol-washing step, however, still has an excessive acid content resulting from high molecular weight sulfonic acids which are not soluble in water or alcohol. This has heretofore made it necessary to neutralize the acid with a basic material such as guanidine or another basic material. The neutralization without recovery of these sulfonic acids in this manner results in a considerable waste of sulfonic acids. We have discovered a method whereby the acid content in the oil phase can be reduced below a critical point so as to make possible the use of the oxidized material and yet permit the recovery of the sulfonic acids per se for use in any manner desired. The recovery of sulfonic acids from the oil phase after treatment of such oil with sulfuric acid presents similar problems and is dealt with in the same manner as utilized in connection with the recovery of sulfonic acids from the oil phase obtained by treatment of the oil with SO_3 .

Each object of this invention is attained by at least one aspect of this invention.

An object of this invention is to provide an improved method for recovery of sulfonic acids. Another object of the invention is to provide a method for the recovery of sufficient sulfonic acids from the oil phase obtained by treating a petroleum fractionation with SO_3 to permit the recovery and use of oxidation products without further neutralization. Another object of the invention is to provide a method for the recovery of water insoluble sulfonic acids resulting from the treatment of a petroleum fraction with SO_3 or H_2SO_4 . Another object of the invention is to concentrate high molecular weight sulfonic acids. Other and further objects of the invention will be apparent upon study of the accompanying disclosure and the drawing.

Broadly speaking, this invention resides in the utilization

2

tion of a mixture of isopropanol and dimethyl formamide as a solvent for the recovery of water-insoluble and alcohol-insoluble sulfonic acids. The result obtained by means of our invention is completely unexpected since dimethyl formamide when used alone fails to recover any more of the sulfonic acids than is obtained by the utilization of isopropanol alone as the solvent.

Better understanding of this invention will be obtained upon study of the accompanying drawing which constitutes a diagrammatic flow scheme utilized in the process of this invention. As pointed out in the Whitney application, identified above, the oil charge stock to the oxidation zone is preferably one which has been purified so as to remove asphalt and other similar impurities therefrom. The oil charge stock is introduced into a treating chamber 11 through inlet conduit 12 and valve 13. A solution of SO_3 in ethylene chloride is introduced into the treating zone through conduit 14 and valve 15 which may, as shown in the drawing, be connected to the oil feed conduit or may be connected separately to the oil treating chamber. During the treatment of the oil within chamber 11, the oil is oxidized with a concomitant production of sulfonic acids. An oil phase is removed from chamber 11 through conduit 16 to the lower end portion of water wash chamber 17.

Water is introduced into the upper end portion of chamber 17 through conduit 18 and valve 19 and is passed through wash chamber 17 in direct contact with the oil phase from chamber 11. A portion of the sulfonic acids are dissolved in the water and are removed from the lower portion of chamber 17 through conduit 21 and valve 22 together with excess water. The overhead effluent from chamber 17 contains the ethylene chloride, oil, oxidized product, and water-insoluble sulfonic acids. The overhead effluent from chamber 17 passes by means of conduit 23 to an intermediate portion of fractionator 24 wherein ethylene chloride is distilled off and removed through effluent conduit 25 and valve 26. The oil, oxidized products, and water-insoluble sulfonic acids are removed from the lower end portion of fractionator 24 and are passed by means of conduit 27 to an intermediate portion of alcohol extraction chamber 28.

Isopropanol or another alcohol, preferably in the C_2 to C_5 range, is introduced into the lower portion of extractor 28 through conduit 29 and valve 31. The alcohol passes upwardly through extractor 28 and through the oil phase, in direct contact therewith. A portion of the water-insoluble sulfonic acids are dissolved in the alcohol extraction step and are removed from the upper end portion of extractor 28 together with excess alcohol through conduit 32 and valve 33. The oil, oxidized products, and alcohol-insoluble sulfonic acids are removed from the lower end portion of extractor 28 through conduit 34 and are passed to an intermediate portion of extractor 35.

A mixture of alcohol, such as used in extractor chamber 28, and dimethyl formamide is used as the solvent in extractor chamber 35. The solvent mixture is introduced into the lower portion of chamber 35 through conduit 36 and valve 37. The solvent is passed upwardly through the oil phase and in direct contact therewith. A considerable portion of the alcohol-insoluble sulfonic acids are dissolved in the solvent mixture and are removed from the upper end portion of extractor chamber 35 through conduit 38 and valve 39. The oil phase containing oxidation products are removed from the lower end portion of extractor chamber 35 through conduit 41 and valve 42. The oxidation products are then separated from the oil in any manner desired and are used without further purification. The sulfonic acids removed by the water extraction, alcohol extraction and alcohol-dimethyl formamide extraction are recovered from the various solvents by

3

means of distillation and are utilized as desirable products of the reaction.

As pointed out above sulfonic acids are also produced by the treatment of an oil fraction with sulfuric acid. When sulfuric acid is utilized as the treating material, it will not be necessary to use the ethylene chloride in the system. Thus, when sulfuric acid is used as the treating agent in chamber 11, each of the recovery steps described above are utilized with the exception of the fractionation step in chamber 24 which is used only to remove the ethylene chloride.

We have discovered that by the use of a mixture of dimethyl formamide and an alcohol (e. g. ethyl, isopropyl, etc.) we obtain a substantial reduction of the acid content of the product obtained from the treatment of oil with SO_3 or sulfuric acid. In this process, the SO_3 or H_2SO_4 treated petroleum fraction which has been water washed and alcohol extracted is extracted one or more times with the mixed solvent. The preferred concentration of dimethyl formamide in the mixed solvent is in the range of between 20 per cent and 80 per cent by weight. The extraction of the acids in the mixed solvent step is usually carried out at a temperature below the boiling point of the solvent at contact conditions, preferably at a temperature within the range of between 70° F. and 180° F. and more preferably at a temperature within the range of between 120° F. and 130° F. The contact is preferably maintained at atmospheric pressure and for a period of between 10 and 30 minutes. The extraction is usually continued until 95 to 98 per cent of the original titratable acidity is removed from the oil phase containing the high molecular weight petroleum sulfonic acids.

The following example is presented for the purpose of clarification and as an aid in more particularly presenting the invention. This example should not be interpreted as unduly limiting the scope of this invention.

Example

3.21 pounds of SO_3 were mixed with 5.3 pounds of ethylene chloride while cooling the mixture by external means. This mixture was added to a mixture containing 20 pounds of propane-fractionated, phenol-extracted SAE 250 lubricating oil and 7.95 pounds of ethylene chloride. The mixture was passed to water extraction in six-foot spinning band glass column of 2-inch diameter. The water-to-oil ratio was held at approximately 1:1 while countercurrent contacting was obtained. Five passes through the column were made, reducing the titratable content of the oil to 1.0 per cent acid expressed as SO_3 . The water-soluble sulfonic acids were removed from the system and the oil mixture was then passed to a distillation column wherein the ethylene chloride was removed. The oil was then batch extracted three times with one volume of isopropanol in each extraction. The first extraction reduced the acid in the oil mixture to 0.24 weight per cent expressed as SO_3 . The second alcohol extraction reduced the acid to 0.20 weight per cent expressed as SO_3 . The third extraction removed practically no acid, leaving an acid content of 0.19 per cent expressed as SO_3 after this extraction.

In an effort to reduce the acid content in the oil phase still further, a small scale extraction was made using dimethyl formamide as the oil solvent. This extraction failed to reduce the acid content of the oil phase. A full scale extraction of the alcohol-extracted oil was made using a 50-50 mixture of isopropanol-dimethyl formamide. A 1:1 volume ratio of the solvent to oil was heated to 180° F. at atmospheric pressure and was then allowed to cool to a temperature between 120° F. and 130° F. The contact was maintained for about 30 minutes and lowered the acid content from 0.19 weight per cent to 0.11 weight per cent expressed as SO_3 . The critical acid content is about 0.14 weight per cent expressed as SO_3 . It will be seen that by the utilization of our invention the acid content of the oil phase ob-

4

tained from the treatment of oil with SO_3 can be reduced to such an extent that further neutralization thereof is unnecessary.

Various modifications of this invention may be made in line with the foregoing disclosure. It is believed that such modifications are clearly within the spirit and scope of this invention.

We claim:

1. The process of recovering sulfonic acids from a petroleum fraction containing said acids, which comprises the steps of contacting said petroleum fraction with a solvent mixture of at least one alkanol, selected from the group consisting of C_2 to C_5 alkanols, and dimethyl formamide, the ratio of said alkanol and dimethyl formamide being in the range of 1:4 to 4:1, at a temperature below the boiling point of the solvent at contact conditions but above 70° F. so as to selectively dissolve said acids in the mixture of alkanol and dimethyl formamide; separating said solvent and acids from said petroleum fraction; and separating said sulfonic acids and said solvent.

2. The process of claim 1 wherein said alkanol is ethanol.

3. The process of claim 1 wherein said alkanol is a C_3 alcohol.

4. The process of claim 1 wherein said alkanol is a C_4 alcohol.

5. The process of claim 1 wherein said alkanol is a C_5 alcohol.

6. The process of claim 1 wherein said solvent-petroleum fraction contacting is carried out at a temperature in the range of between 70° F. and 180° F.

7. The process of claim 6 wherein said solvent-petroleum fraction contact is maintained for a period of between 10 and 30 minutes.

8. A process for removing sulfonic acids from a petroleum fraction containing said acids, which process comprises contacting a liquid phase of said petroleum fraction with a separate liquid phase of a solvent mixture comprising at least one alkanol containing from 2 to 5 carbon atoms per molecule and dimethyl formamide, the weight ratio of said alkanol to dimethyl formamide being in the range 1:4 to 4:1, maintaining said solvent substantially in the liquid phase during said contacting, and separating a liquid phase rich in said solvent mixture from a liquid phase rich in said petroleum fraction.

9. A process for recovering sulfonic acids from a petroleum fraction containing said acids, which process comprises the steps of contacting said petroleum fraction with a solvent mixture of isopropanol and dimethyl formamide in which the weight ratio of isopropanol to dimethyl formamide is within the range 1:4 to 4:1, at a temperature below the boiling point of said solvent mixture at contacting conditions but above 70° F. so as to selectively dissolve said acids in said solvent mixture, separating said solvent mixture and acids from said petroleum fraction, and separating said sulfonic acids from said solvent mixture.

10. In a process of recovering sulfonic acids from a petroleum fraction containing said acids, which comprises the steps of contacting said petroleum fraction with water so as to selectively dissolve a portion of said sulfonic acids in said water; separating said water and dissolved acids from said petroleum fraction; contacting said petroleum fraction and at least one solvent alcohol so as to dissolve a portion of said sulfonic acids in said alcohol; separating said alcohol and dissolved acids from said petroleum fraction; the improvement which comprises contacting said petroleum fraction and a solvent mixture of an alkanol containing from 2 to 5 carbon atoms per molecule and dimethyl formamide at a temperature below the boiling point of the solvent at contact conditions but above 70° F. so as to dissolve sulfonic acids in said solvent, the weight ratio of said alkanol to dimethyl formamide being in the range 1:4 to 4:1; separating

ing said solvent and dissolved acids from said petroleum fraction; and recovering said sulfonic acids from said solvents.
